ADVERTISING DEVICE

Henry James Moorhouse, Superior, Wis.

Application October 1, 1946, Serial No. 700,483

3 Claims. (Cl. 312—125)

1

This invention relates to an advertising device and more particularly to a movable display device for advertising and sales purposes.

The principal object of this invention is the provision of an advertising device which is adapted to hold a plurality of articles for display, and which displays them one at a time.

Another object of this invention is the provision of an advertising device which is adapted to display a plurality of articles by rotating each of said articles to expose its several sides to view.

Another object of this invention is the provision of an advertising device for the display of a plurality of articles, each article being displayed separately from the rest, the display device being provided with a screen behind which the different articles are moved in order to bring them into display position, one at a time. In other words in this device the apparatus and means by which the several articles are moved from a hidden position to a display position are at no time disclosed to the audience.

A further object of this invention is the provision of an advertising device in which the several articles on display are moved into and out of display position by means of a movement of revolution, and in which each of the articles on display is caused to engage in movement of rotation to display its several sides to the public view.

These and other objects are attained by the mechanism shown on the accompanying drawing in which—

Fig. 1 is a vertical section therethrough;

Fig. 2 is a horizontal section on the lines 2—2 of Fig. 1;

Fig. 3 is a fragmentary section showing the means by which the display device causes articles on display to engage in movement of revolution;

Fig. 4 is a fragmentary section showing the locking mechanism by which movement of revolution is prevented at predetermined time intervals;

Fig. 5 is a horizontal section on the line 5—5 of Fig. 1; and

Fig. 6 is a horizontal section substantially similar to that of Fig. 2 showing the screen behind which the movement of revolution takes place moving into screening position.

The advertising device herein claimed is provided with a base 10, a substantially cylindrical side wall 11, and a cover or roof 12. In the base 10 is an electric motor 15 which operates through a speed reducing gear box 16 to drive the mechanism hereinafter described. A shaft 18 is con-

nected to the gear box 16 and to a bearing 17 in ceiling 19. Ceiling 19 is situated immediately below the roof or cover 12, and it is provided with an opening 20 for electric light bulb 21 affixed to the roof 12. It is through this opening 20 that light from bulb 21 is enabled to reach and flood the articles on display.

Fixedly mounted to shaft 18 at the bottom thereof is a screen supporting disc 25, said disc supporting screen 26 as shown in Fig. 1. It will be noted in Fig. 2 that the screen extends about one-sixth of the way around the cylindrical or substantially cylindrical wall 11 and that it is curved in conformity with said wall. Since disc 25 is affixed to shaft 18, said disc will rotate with said shaft and since screen 26 is affixed to said disc, said screen will accompany said disc in its rotary movement. The screen of course engages in movement of revolution. A preferred speed is approximately two revolutions per minute. The speed is controlled by the gear ratios in the gear box 16. No particular showing is made of the gears within this box for the reason that it is conventional equipment. Also affixed to shaft 18 is a double gear wheel 30, this gear wheel being positioned immediately above disc 25. Since this double gear wheel which may just as well be a pair of gear wheels is affixed to the shaft 18, rotation of said shaft causes corresponding rotation of said gear wheel.

Rotatably mounted above said gear wheel is a second disc 32. This disc may be considered to be the floor of the display device, since it is on this disc that the articles are placed for display purposes. Another disc 33 is rotatably mounted on shaft 18 a pre-determined distance above floor disc 32.

Partitions 34 are vertically and radially disposed between said discs 32 and 33, and they are affixed to said discs by means of bolts 35.

These bolts hold the entire assembly comprising discs 32 and 33 and partitions 34 together.

Reference to Fig. 1 shows that these partitions are provided with reflecting surfaces. Reference to Fig. 2 will disclose that these partitions number six in the preferred embodiment, and that they are arranged radially at equal distances from each other. Triangular shaped compartments therefore are provided between adjacent partitions 34 for the reception of articles to be displayed.

A small disc-shaped platform 50 is rotatably mounted on the disc 32 in each of said compartments. Affixed to three of these rotatably mounted discs, to wit, 50a, 50b and 50c are gear wheels 51. And affixed to the last three of these rotatably mounted discs, to wit, 50d, 50e

and 50_f are gear wheels 52. There is no important difference between gear wheels 51 and 52, except that they lie on different but parallel planes. A gear chain 54 interengages intermittent gear wheels 51 with the upper unit of gear wheel 30, and gear chain 55 interengages gear wheels 52 with the lower unit of gear wheel 30. In consequence of such arrangement when gear wheel 30 is caused to rotate with shaft 18, corresponding rotation of platform discs 50 is also caused.

It will hereinafter be shown that the floor disc 32 engages in intermittent angular movement. Since the platform discs 50 are mounted on floor disc 32 they, too, will engage in intermittent angular movement at the same time that they engage in constant uniform rotational movement. An article mounted on one of the platform discs 50 will rotate with that disc on the disc's own axis. And it will also move in a circular movement around the shaft 18 when the platform discs 50 engage in such movement.

It will be seen in Figs. 1 and 3 that affixed to disc 25 is a vertically movable latch pin 60. A compression spring 61 on said pin tends to urge it downwardly. A ramp 62 is affixed to the base 10 at its front end. This ramp is adapted to engage the pin 60 when the disc 25 brings said shaft around to the place where said ramp is located. When the ramp engages the pin, it does so against the action of spring 61 and it moves said pin upwardly until it engages a downwardly extending projection or lug 65 affixed to the bottom of the floor disc 32. The ramp 62 has a length of approximately one-sixth of the circumference of the device as a whole. When it engages the pin 60, therefore, and causes said pin to engage lug 65 on the floor disc 32, such engagement will be maintained for a distance of approximately one-sixth of said circumference, so that as the disc 25 rotates at the rate of two revolutions per minute, it will engage the lug 65 twice in one minute and cause said lug to move two-sixths of the distance around the shaft 18. In other words every thirty seconds lug 65 will be engaged by pin 60, and it will be caused to move one-sixth of the distance around shaft 18. In consequence of such movement of lug 65, the floor disc 32 will turn around shaft 18 for a distance corresponding to the angular width of each of the compartments formed by the partitions 34. In this manner each compartment is brought into view every three minutes.

A mechanism is provided whereby the assembly 32, 34 and 33 may be locked into fixed position between the intermittent angular movements above described. This locking mechanism is best shown in Figs. 4 and 5. It comprises a cam 70 affixed to the shaft 18, said cam being adapted to engage a roller 71 on horizontal shaft 72 against the action of compression spring 73 on said shaft. The shaft 72 is carried by bearings 74 and 75 which are affixed to the disc 19. At the free end of the shaft 72 is a downwardly extending member or projection 76. It will be noted in Fig. 5 that disc 33 is provided along its circumferential edge with cut-outs or notches 77. More particularly it is provided with six notches arranged equidistant from each other. The projection 76 is adapted to enter notches 77 when shaft 72 is disengaged by the cam 70, and spring 73 is permitted to act upon shaft 72 without the opposition of cam 70.

The normal position of shaft 72 therefore is the inward position, whereby the projection 76

is in engagement with one of the notches 77. When the cam 70 acts upon the shaft 72 however the projection 76 is caused to disengage the notch 77 in question. The cam 70 is affixed on shaft 18 to synchronize its camming action with the engagement of pin 60 with lug 65 previously discussed. That is the locking mechanism shown in Fig. 5 is in locking engagement with the disc 33 at all times except when the pin 60 is in engagement with the lug 65. At such time the cam 70 disengages the locking mechanism from the disc 33 and permits said disc to engage in angular movement in response to the action of pin 60 and upon the lug 65.

15 The front of the device hereinabove described is open at 80. The opening extends about one-sixth of the way around the circumference of the device and in that respect it corresponds to the dimensions of the screen 26 and compartments 20 formed by the partitions 34. Only one compartment is exposed to view at any one time through the opening 80. Each compartment is thus exposed less than thirty seconds at any one time. At the end of the exposure period, the screen 26 25 moves into position across the opening 80 carrying with it the next compartment to be exhibited. As the screen passes on, the pin 60 will drop off the ramp 62 to disconnect the pin from contact with the lug 65, leaving the thus moved compartment in exposed position. At the same time, the cam 70 has turned the projection 76 to lock the compartment in this position. The screen now moves away from the opening 80, and that second compartment is now exposed to view through said opening 80. Each of said compartments is provided with an opening 90 in the disc 33, said opening 90 being adapted to register with the opening 20 when the compartment in which it is situated is brought to the front of the advertising device 40 and is exposed to view. Thus it is that each time a compartment is exposed to view it is flooded with the light from the light bulb 21. This feature taken together with the fact that each compartment is provided with a pair of reflecting surfaces 40 disposed at an acute angle to each other, makes for a very striking display construction for many types of article. Especially is this the case when it is remembered that the article on view rotates continually while in view.

It will be appreciated that what has above been described is but a preferred embodiment of this invention and that variations and modifications may be incorporated therein without departing from the basic principles of the invention. 55 For example all six platform discs 50 are shown to be adapted for continual rotation. It will be appreciated that when only one of the chains 54 and 55 is used, only half of the platform discs 50 will be caused to rotate. The other three will remain stationary with respect to the disc 32. Another illustration of a modification in this device may be found in varying the number of compartments into which the device is divided. Although six are shown in the drawing, a greater or a lesser number may be used.

I claim:

1. An advertising device comprising a housing having a lateral opening, a rotatable disc mounted within said housing and having a screen vertically connected to the edge thereof within and adjacent the walls of the housing, said screen adapted to intermittently close said opening as the disc is moved, a compartmented display device rotatably disposed within the hous-

ing above said disc, latch means on the disc movably to engage said device and normally out of engagement therewith, a cam means in the housing adjacent the lateral opening and adapted to engage said latch means as the disc is rotated to lift said latch means into engagement with said device to cause a predetermined rotation of said device, said device being provided with a plurality of smaller discs disposed in the compartments and means for causing rotation of said smaller discs independently of the rotation of the display device.

2. An advertising device comprising a housing having a lateral display opening, a rotatable disc in the housing, a screen supported on said disc in a plane close and parallel to the wall of the housing, a rotatable shaft connected to said disc to rotate the same, a compartmented display device rotatably disposed around said shaft above said disc, a movable latch pin on the disc adapted to be moved into engagement with said display device, a cam means within the housing adjacent the opening therein to engage the latch pin and move it into engagement with the display device whereby the display device is rotated a predetermined distance when the screen is moved across said opening, cam means on said shaft, and a latch member mounted on the housing and operatively associated with said cam and normally adapted to engage the display device to hold it stationary, said cam operating said latch member to release the device just prior to the engagement of the latch pin with the display device to move the same.

3. An advertising device comprising a housing having a lateral display opening, a disc disposed horizontally within the housing below said opening, a rotatable shaft connected to said disc and extending vertically upward through the housing, a compartmented display device rotatably

10

15

disposed around said shaft, a screen connected to the periphery of said disc and extending vertically parallel to the wall of the housing, said screen adapted to be moved periodically past said display opening, a latch pin on the disc adjacent the forward edge of the screen and adapted to be moved upwardly to engage this display device, a cam means in the form of a ramp disposed in the housing below the display opening to move the latch pin into engagement with the display device, a cam on the upper end of the rotatable shaft, a latch shaft mounted on the housing and engageable with said cam, a latch element on the end of said shaft normally adapted to engage said display device to hold said device stationary, said cam operatively arranged to release said latch element from engagement with the display device just prior to the engagement with said device of the latch pin whereby said display device can be moved a predetermined distance as the screen passes the display opening.
